UNITED STATES PATENT OFFICE.

JAMES MICHAEL FARMER, OF HAMPTON, ENGLAND.

AUTOMATIC MUSICAL INSTRUMENT.

SPECIFICATION forming part of Letters Patent No. 443,909, dated December 30, 1890.

Application filed September 24, 1890. Serial No. 365,975. (No model.)

To all whom it may concern:

Be it known that I, JAMES MICHAEL FARMER, engineer, a subject of the Queen of Great Britain, residing at Esher Villa, Belgrave 5 Road, Hampton-on-Thames, in the county of Middlesex, England, have invented an Automatic Musical Instrument; and I do hereby declare that the following is a full, clear, and exact description of the invention, which will 10 enable others skilled in the art to which it appertains to make and use the same.

The invention relates to that class of musical reed instruments in which a perforated endless traveling band is employed in connection with a concertina-bellows to govern the 15 passage of air to the vibrating reeds; and the invention consists in a simple device for giving motion to the feed-roller in one direction only, in means whereby a single scale of reeds 20 is caused to produce the effect of a double set during the expansion and contraction of the bellows, and in various details of construction hereinafter more fully described; and in order that the said invention may be more 25 clearly understood and readily carried into effect I will proceed, aided by the accompanying drawings, more fully to describe the same.

In the drawings, Figure 1 is a longitudinal section, taken on the line 1 1 of Fig. 3, of an 30 instrument constructed according to my invention. Fig. 2 is a longitudinal elevation thereof. Fig. 3 is an under side view thereof. Fig. 4 is a transverse section taken on the line 2 2 of Fig. 1, and looking toward the left. Fig. 35 5 is a similar view looking toward the right. Fig. 6 is a portion of Fig. 1, but drawn full size. Fig. 7 is a side elevation thereof. Fig. 8 is an end elevation thereof. Fig. 9 is an under side view thereof with part of the cover 40 of the music-box broken away. Fig. 10 is a side view of the cover of the music-box and connected parts separately. Fig. 11 is an end view thereof, and Fig. 12 is an inside view thereof.

45 In the several figures like parts are indicated by similar letters of reference.

a a* represent the bellows, a' a** represent the end caps thereof, and b represents a valve-box, which is located centrally of the bellows 50 and divides it into two parts a a*, so as to constitute a double-acting instrument, and the outer ends of the caps a' a** are con-

nected together by means of bars a³ fixed thereto, but not to the central valve-box b, and formed with long slots a^{2*} thereon. 55

At the sides of the valve-box b are provided projections b'*⁵, which travel in the slots a^{2*} of the bars a³, in order to guide the valve-box b in its movements, and to these projections b'*⁵ are fixed the inner ends of two bars 60 or rods b', which pass through guides a^{2**} upon the bars a³, and extend beyond the end cap a'*⁵ of the bellows a*, and are there connected by a cross-head b², pivoted thereto at b^{2*} for convenience in use, and to which is 65 attached one of the usual loops or straps x, under which is placed the hand of the performer, the other of such loops or straps x being attached to the end cap a'*⁵ of the bellows a at the opposite end of the instrument. 70 By this arrangement of parts the central valve-box b may be moved to and fro, alternately compressing and expanding the bellows a a*.

The valve-box b is divided into two parts 75 b* b** by a horizontal partition b³, and to the lower part b** thereof is fixed the music-box b⁸, within which is located the reed-chamber c, which is fitted with a single scale of reeds c' and is open to the lower part b** of the 80 valve-box b.

The bellows a* communicates by a way b⁴ with the lower part b** of the valve-box b, while the other bellows a communicates therewith by a way or conduit b⁵, and valves b^{4*} 85 b^{5*} are employed to close the airways b⁴ b⁵ during the compression of the bellows a a* and to open them during the expansion thereof, while the waste air is exhausted from the bellows during their compression through 90 other valves b⁶ b⁷, which close during their expansion. Air will thus be drawn through and will sound those of the single scale of reeds that are not covered by the endless perforated band f during the movement of the 95 valve-box b and bellows a a* in either direction and during the consequent expansion of either of such bellows.

Motion is given to the roller d, which feeds forward the endless perforated band f of 100 music across the wall of the reed-chamber c, by the following means: The feed-roller d is provided with necks or axes of motion d', which are mounted in bearings formed in

the walls of the music-box b^8 , and one of such axes passed through the wall of the music-box b^8 , and has fixed thereon a pulley d^2 , formed with double grooves d^{2*} d^{2**} there-
5 in and at intervals the feed-roller d is fitted with india-rubber bands d^3 , which enable the roller d to obtain a proper grip of the endless band f of paper, as hereinafter described.

To a stud upon the end cap a' of the bell-
10 lows a is attached one end of a cord e , and this cord e thence passes over a guide-pulley e' , mounted upon a stud e'^* , carried by the end wall of the valve-box b , thence over and completely around one division d^{2*} of the
15 double grooved pulley d^2 , thence over an idle or guide pulley e^2 , mounted upon a stud e^{2*} , fixed to the music-box b^8 , thence under and around the other division d^{2**} of the grooved pulley d^2 , and thence over a stud to a cleat e^3
20 upon the cap a'^* of the bellows a^* . By this ar-
rangement of parts the cord e , during the in-
ward movement of the cap a' upon the com-
pression of the bellows a will be slackened and will therefore slip upon the groove d^{2*} of
25 the pulley d^2 , while upon the simultaneous outward movement of the cap a'^* and corre-
sponding expansion of the bellows a^* the cord will bind upon the groove d^{2**} of the pulley d^2 and rotate the feed-roller d . The same
30 action will take place upon the expansion of the bellows a , but in that case the cord will bind upon the groove d^{2*} , the act of drawing the cord e off the pulley d^2 causing it to bind thereon, so that whichever bellows a or a^* is
35 expanded the feed-roller d will be rotated, and by reason of the direction in which the cord e is passed around the groove of the pulley d^2 the feed-roller d will always travel in one direction.

40 The music-box b^8 is formed open at its sides in order to allow of the passage of the endless band f of music, and it is perforated upon its under side to permit the musical sounds to issue therefrom without obstruction.

45 The bottom or cover b^9 of the music-box b^8 I form readily detachable therefrom to allow of the endless band f being placed in position, and the cover is provided with fixed hooks b^{10} to engage corresponding studs b^{10*}

50 upon the music-box b^8 , and the music-box b^8 is provided with pivoted hooks or catches b^{11} to engage corresponding studs b^{11*} upon the

cover b^9 , by which means the cover is capable of being readily attached to the music-box b^8 , or of being detached therefrom when desired. 55

Upon the inside of the cover b^9 of the music-box b^8 is mounted in bearings with capa-
60 bility of revolution a roller b^{12} , which im-
pings upon the rubber rings d^3 of the feed-
roller d , and thus causes such roller d to ob-
tain a proper grip of the endless band f , and the endless band f is guided in its movements by projecting ribs or flanges b^{13} , fixed upon the outer wall of the reed-chamber c . 65

By arranging the means for giving motion 65 to the feed-roller d upon the exterior of the instrument, I am enabled more readily to adjust the same than heretofore.

Having now particularly described and as-
certained the nature of my said invention and 70 in what manner the same is to be performed, I declare that what I claim is—

1. An automatic musical instrument formed with a central valve-box b , a separate bellows a a^* upon each side of such valve-box, bars 75 a^2 , connecting the end caps a a'^* of such bellows, a cross-head b^2 , connected by bars b' with the valve-box b , a scale of musical reeds c' , arranged within a reed-chamber located in a music-box b^8 , and suitable ways closed by 80 valves for the admission of air to the bellows and for the exhaustion of such air, substan-
tially as herein shown and described.

2. In an automatic musical instrument, the combination of a central valve-box b , a sepa-
rate bellows a a^* upon each side of such valve-
box, bars a^2 , connecting the end caps a a'^* of 85 such bellows, a cross-head b^2 , connected by bars b' with the valve-box b , a scale of mu-
sical reeds c' , arranged within a reed-cham-
ber located within a music-box b^8 , suitable 90 ways closed by valves for the admission of air to the bellows and for the exhaustion of such air, a feed-roller d , provided with a double-grooved pulley d^2 , guide-pulleys e' e^2 , 95 and a length of cord e , passed around such pulleys and at each end fastened to the end caps of the instrument, substantially as here-
in shown and described, and for the purpose stated.

JAMES MICHAEL FARMER.
